DESIGN FOR A CASKET

William Edward Thompson, Burlington, Iowa, assignor to Embalming Burial Case Company, Des Moines, Iowa, a corporation of Iowa

Application February 18, 1935, Serial No. 55,485

Term of patent 7 years

To all whom it may concern:

Be it known that I, William Edward Thompson, a citizen of the United States, and a resident of Burlington, in the county of Des Moines and State of Iowa, have invented a certain new, original, and ornamental Design for a Casket, of which the following is a specification, reference being had to the accompanying drawing, forming part thereof.

Figure 1 is a top plan view of a casket embodying my invention.

Figure 2 is a side elevation of the casket; and Figure 3 is an end elevation of the casket.

I claim:

The ornamental design for a casket, substantially as shown.

WILLIAM EDWARD THOMPSON.

CERTIFICATE OF CORRECTION.

Design No. 95,388.

April 23, 1935.

WILLIAM EDWARD THOMPSON.

It is hereby certified that the residence of the assignee in the above numbered patent was erroneously written and printed as "Des Moines, Iowa" whereas said residence should have been written and printed as Burlington, Iowa, as shown by the records of assignments in this office; and that the said Letters Patent should be read with this correction therein that the same may conform to the record of the case in the Patent Office.

Signed and sealed this 25th day of June, A. D. 1935.

Bryan M. Battey
